UNITED STATES PATENT OFFICE

2,560,774

DRIVING AND ADJUSTING MEANS FOR
PRINTING ROLLERS IN WEB PRINT-
ING MACHINES

Carlos Luttenauer, Mulhouse, France

Application October 24, 1946, Serial No. 705,290
In France February 16, 1946

6 Claims. (Cl. 101—248)

1

The invention relates to the drive and adjustment of the engraved rollers in rotary machines for printing fabrics and the like.

It is known that in the machines used heretofore, the drive of the printing rollers is effected by means of a large central gear or "crown" wheel (or by two gears of this kind in so-called double-face machines) fixed on a rotary shaft, near one of the side plates of the frame of the machine, and driving the whole group of small control pinions fixed on the ends of the shafts of the printing rollers which are mounted around the pressure cylinder. It has been admitted that, when the number of colours is large, the diameter of the central gear is very large relatively to that of the control pinions and that this consequently involves, when starting, a considerable expenditure of energy to overcome, first of all the inertia, then the resistance caused by the pressure exerted on the printing rollers, which is a first drawback.

Another drawback consists in the fact, that, owing to the various inclinations of the printing rollers relatively to the pressure cylinder and also to the variations of the distances of the axes of said rollers from that of the pressure cylinder due to the different diameters of the rollers which may have to be used, it is impossible to secure a correct meshing of the control pinions with the large central gear, so that the flanks of the teeth quickly become worn and require frequent replacements which involve considerable costs for upkeep.

On the other hand, as regards the bringing into step to secure the accurate registering of the patterns of the various rollers, it is known that this operation, in the known machines, is awkward and dangerous for the operator when it is effected while the machine is in motion, owing to the fact that the operator has to act on small worms provided on each control pinion in order to impart to the printing rollers complementary rotations of very small amplitude in one or the other direction. This operation therefore requires very special skill and attention on the part of the operator, whose safety is thus seriously jeopardized in view of the high speeds of rotation at which there is a greater and greater tendency to operate rotary printing machines.

The invention has for its object to eliminate all these serious drawbacks and to provide, to this end, a device for driving and adjusting the printing rollers which is mainly characterized in this that the said rollers are operated by a driving and adjusting station forming a separate unit

2

from the machine and comprising a plurality of rotary driving members, the number of which is equal to that of the rollers and each of which is connected to the corresponding roller through the intermediary of a transmission which is housed in the said station and which comprises a universal joint connection and a telescopic intermediate shaft interposed between the shaft of the said rotary driving member and that of the said roller.

Each rotary member of the driving and adjusting station which drives a printing roller preferably comprises a gear case which is furthermore provided with means enabling, by the operation of an adjusting member provided at the said station and corresponding to the said roller, a complementary partial rotation in the desired direction to be imparted, for bringing the roller into step, to the gear case and, through the intermediary of the universal transmission, to the shaft of the printing roller.

At the driving and adjusting station, the adjusting members for bringing the rollers into step, for example hand wheels, are arranged, symmetrically and in the numerical order of the rollers, on a panel.

Preferably, each wheel or other adjusting member, is combined with reference means (not shown) such as a pointer moving in front of a graduated dial, indicating to the operator the direction and the amplitude of the adjustment for each printing roller.

Each transmission comprising universal joints is preferably provided with a coupling or clutch enabling the corresponding printing roller to be made operative or inoperative at will.

It will be readily understood that, by means of the driving and adjusting device, it will henceforth be possible to effect the bringing into step individually for the rollers by means of hand-wheels located in stationary positions during the operation of the machine, thereby greatly facilitating the adjustment and eliminating all risk of accidents for the operator. On the other hand, the transmission by means of universal joints and a telescopic shaft allows the axis of each printing roller to effect slight displacements so as to take up oblique positions with respect to the axis of the pressure cylinder. It furthermore allows of any variations of the distance between the axis of the pressure cylinder and that of the printing roller in the case in which said printing roller is replaced by a roller of different diameter, and it also allows of an axial displacement of the printing roller in both di-

rections, either for the adjustment, or owing to expansion.

In order to make the invention more clearly understood, and merely by way of a non-limitative example, an embodiment thereof is described hereinafter and diagrammatically illustrated in the accompanying drawings, in which:

Fig. 1 is a view in front elevation, partly in vertical section, of the device for driving and adjusting the printing rollers of a printing machine;

Fig. 2 is a partial view in horizontal section of the said device;

Fig. 3 is a view thereof in vertical section along III—III (Fig. 1);

Fig. 4 is a sectional view of the transmission comprising universal joints, interposed between the driving and adjusting device and the shaft, shown in the operative position, of one of the printing rollers;

Fig. 5 is a view of the coupling of the shaft of the printing roller, in a plane at right angle to that of Fig. 4;

Fig. 6 is a view, in the same plane as that of Fig. 4, of the coupling device, the shaft of the printing roller being assumed to be in the inoperative position;

Fig. 7 is a diagrammatic elevational view showing the arrangement of the gears of the driving station;

Fig. 8 is a view in longitudinal vertical section of a gear case corresponding to one of the printing rollers; and

Fig. 9 is a detail view in transverse section of the gears housed inside the said case.

In these figures, 1, 2 and 3 are the three first printing rollers located on the same side of the vertical plane of symmetry of the machine, of a rotary printing machine having six rollers; 7 is one of the side frames acting as a support for the bearings 8 of the six rollers; 9 is the driving and adjusting station of the machine, having on its front face a panel 10 on which are symmetrically arranged the hand-wheels 1', 2', 3', 4', 5', 6' respectively serving for the individual adjustment of the six printing rollers, for bringing them into step; 11 is a case which is fixed to the casing 9 of the station, by one of its walls 12, and inside which are housed the universal joint connections which transmit the drive individually to each of the printing rollers; 13 is the other end wall, or bottom, of the said case, opposite the frame 7. The driving and adjusting station 9 comprises a driving pulley 14 whose movement is transmitted through a gear train 15—16—17—18—19—20—21 to an intermediate gear 22 with which mesh control pinions 23, six in number in the example shown, each corresponding to one of the printing rollers.

Between each of the control pinions 23 and the corresponding printing roller is interposed a transmission comprising universal joints 24 and 25 and a telescopic shaft 26 of which one of the portions, which is of square cross-section with canted corners, can slide in a bore of like cross-section of the other portion. This device enables, as stated, the printing roller to take up oblique positions in the horizontal and in the vertical directions with respect to the axis of the pressure cylinder; it furthermore allows of a variation of the distance between the axis of the printing roller and the pressure cylinder, and also of the axial displacement of the printing roller.

The device furthermore comprises a coupling sleeve 27 controlled by a fork 28 secured to an operating lever 29, which enables the square end

30 of the shaft of the roller to be coupled to or uncoupled from the universal joint transmission, a hand-wheel 31 acting on a conical compression device enabling the square end 30 to be locked.

With regard to the adjustment for bringing into step, it is obtained, for each roller, through the intermediary of a mechanism housed inside a case 33 secured to the control pinion 23. Said case contains a worm wheel 34, which is secured to the end of shaft 32 driven by the pinion 23 of the universal joint transmission, and which can be actuated by a worm 35 of which the shaft can be driven, through the intermediary of gears 36, 37, 38, by a pinion 48 meshing with the circular grooves 39^a, forming rack teeth, of a cylindrical rod 39 which can be driven, in its turn, by a pinion 40 of a shaft 41 which can be driven through the intermediary of gears 42, 43, 44, by the shaft 45 of the corresponding hand-wheel, 2' for example (the hand-wheels 1' and 3' acting in the same manner, whereas the shafts 45 of the hand-wheels 4', 5' and 6' drive directly by means of their pinion 40 the corresponding cylindrical rack 39).

During the operation of the machine, the control pinion 23 rotates continuously driving the printing roller; the gear case 33, with all the members which it contains, including the worm wheel 34, rotates loosely about the axis of the cylindrical rack 39, the pinion 38 likewise rotating, with its teeth meshing with the rack, without causing any rotary movement of the worm wheel 34. When the printing work requires one of the rollers, 2 for example, to be brought into step, the hand-wheel 2' is rotated in the required direction, which produces an axial displacement of the cylindrical rack 39 and therefore a certain rotation of the rack pinion 48. Owing to this, through the intermediary of the gears 38, 37, 36, the worm 35 rotates and, consequently, the worm wheel 34 also rotates a certain amount and likewise the stub-shaft 32 of the universal joint transmission and, finally, the printing roller effects the desired complementary partial rotation for bringing it into step.

The hand-wheels 1', 2', . . . 6' therefore remain stationary during the operation of the machine and the adjustment can be marked by reference means (not shown), for example, a pointer which is secured to the hand-wheel and which co-operates with a graduated sector.

It is of course understood that it is possible, without exceeding the framework of the invention, to imagine modifications and improvements of details, and also to make use of means forming equivalents of those given by way of examples.

I claim:

1. In a printing machine having a plurality of printing rollers, in combination, a driving gear, a plurality of driven gears entrainable by said driving gear, coupling means connecting each of said driven gears with a respective printing roller and embodying mechanism for angularly displacing said printing rollers relatively to the respective driven gear and to one another, said mechanism including a housing secured to each one of said driven gears and rotatable therewith, a shaft forming part of said coupling means and non-rotatable with respect to the related printing roller, said shaft extending into said housing and being rotatable relative to the latter, a pinion journaled in said housing to rotate about an axis normal to the axis of rotation of the latter, irreversible transmission means

coupling said pinion with said shaft so that said shaft normally rotates with said housing and may be angularly displaced relative to the housing by rotation of said pinion, and a non-rotatable cylindrical control member extending coaxially into said housing, said control member having peripheral grooves, said pinion having teeth adapted to lie idly in said grooves when said housing is rotated about said control member, said control member being axially displaceable relative to said housing so as to vary the angular position of said driven gear relative to said shaft.

2. The combination according to claim 1 wherein said shaft has a central bore, said control member comprising a non-rotatable cylindrical rod slidably extending into said bore.

3. The combination according to claim 1, comprising a rotatable operating member journaled in a stationary part of the machine, and a mechanical coupling between said operating member and said control member for converting the rotation of the former into an axial displacement of the latter.

4. In a printing machine having a plurality of printing rollers, in combination, a driving gear, a plurality of driven gears meshing with said driving gear, transmission means connecting each of said driven gears with a respective printing roller, said transmission means including a shaft for each roller, a housing secured to each of said driven gears, respectively, and rotatable therewith, the associated shaft extending into said housing, a worm wheel in said housing fixed to said shaft, a worm journaled in said housing for rotation about an axis at right angles to the rotational axis of said housing and meshing with said worm wheel, a pinion journaled in said housing rotatable about an axis parallel to the axis

of said worm, a gear means interconnecting said pinion with said worm, a plurality of non-rotatable cylindrical control members each extending into a respective one of said housings in coaxial relation thereto, said control member having peripheral grooves, each of said pinions having teeth adapted to lie idly in the grooves of the respective control member when the associated housing rotates about the latter, and a plurality of operating members for axially displacing said control members, respectively, whereby the relative angular positions of the printing rollers may be adjusted.

5. The combination according to claim 4 wherein said transmission means further includes a pair of telescoped drive members adapted for simultaneous rotation, a first universal joint securing said shaft to one of said drive members, and a second universal joint securing the printing roller to the other of said drive members.

6. The combination according to claim 5, further comprising a manually operable clutch for detaching each of said second joints from the respective printing roller.

CARLOS LUTTENAUER.
